UNITED STATES PATENT OFFICE.

GEORGE OHMER, OF DAYTON, OHIO.

DESIGN FOR A PLEASURE-BOAT.

SPECIFICATION forming part of Design No. 21,031, dated September 8, 1891.

Application filed May 13, 1891. Serial No. 392,631. Term of patent 3½ years.

To all whom it may concern:

Be it known that I, GEORGE OHMER, a citizen of the United States, residing at Dayton, in the county of Montgomery and State of Ohio, have invented and produced a new and original Design for a Pleasure-Boat; and I do hereby declare the following to be a full, clear, and exact description of the same, reference being had to the accompanying drawing, forming a part thereof.

The figure is a side elevation of the boat.

The feature of the invention is the design for a pleasure-boat having, with the hull and attached open-work, the shape of a water-fowl.

The design consists in a boat having one or more hulls provided with lattice-work, the

whole having the shape of a swan with extended wings. The canopy shown in the illustration forms no part of the design. 20

I claim—

A design for a pleasure-boat having the hull of the usual configuration and above the same latticed work, which, with said hull, has the resemblance in shape to that of a swan with spreading wings, substantially as shown and described. 25

In testimony whereof I affix my signature in presence of two witnesses.

GEORGE OHMER.
